STOOL OR SIMILAR ARTICLE

Arthur W. Ellsworth, South San Gabriel, and Robert K. Fujioka, Los Angeles, Calif., assignors to Samsonite Corporation, Denver, Colo., a corporation of Colorado

Original design application June 7, 1965, Ser. No. 85,609.
Divided and this application Sept. 5, 1967, Ser. No. 9,702

Term of patent 14 years

Int. Cl. D6—01

U.S. Cl. D15—8

FIG. 1

FIG. 2

FIG. 3

FIG. 4

FIG. 6

FIG. 5

FIGURE 1 is a perspective view of a stool or similar article showing our design wherein the top is formed of a plurality of slat members;

FIGURE 2 is a side elevation view;

FIGURE 3 is a rear elevational view thereof;

FIGURE 4 is a modified form of the stool or similar article of FIGURE 1 wherein the top is a single piece rather than a plurality of slats;

FIGURE 5 is a side elevational view; and

FIGURE 6 is a rear elevational view thereof.

This application is a division of our copending application Ser. No. D. 85,609 filed June 7, 1965, now U.S. design patent D. 208,698 dated Sept. 26, 1967.

We claim:

The ornamental design for a stool or similar article, as shown and described.
